UNITED STATES PATENT OFFICE.

JOSEPH McBRIDE, OF VANCOUVER, BRITISH COLUMBIA, CANADA.

AMUSEMENT DEVICE.

Application filed July 25, 1928. Serial No. 295,175.

My invention relates to improvements in amusement devices the objects of which are to provide means whereby two or more players may test their skill one against the other in a manner which is both amusing and entertaining, and to provide a device which can be employed by showmen and others as a lucrative attraction for the public. The device in its present forms 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 one or both end walls of the tank is a plurality of steering shafts 14 each having a steering wheel 15 at its outer end and a sheave 16 at its inner end. An endless cord 17 extends between one of the sheaves 16 and one of the sheaves 10 of a track 7, so that as the steering wheel 15 is turned the corresponding track 7 is rocked in a similar direction. Fitted below the transverse centre of the tank 1 is a stationary shaft 18 upon which a plurality of independently movable arms 19 are swingable. These arms each have an upward extension 20 operatively connected by a rod 21 to the lower extremity of a hand lever 22, as at 23, so that as the lever is pulled in one direction by a player its arm 19 is swung in an opposite direction. A dash pot 24 of any suitable type is interposed between the lever 22 and a stationary part of the device for the purpose of retarding the swing of the arm 19. An arcuate member 25 is provided for each arm 19 which carries a plurality of rollers 26 for the purpose of forming a guide for a light cable 27. The cable 27 extends in opposite directions from the outer end of the arm 19 about the rollers 26, up and over suitable sheaves 28 on the upper edge of the end walls 4 thence downwards inside the tank 1 around sheaves 29 through the apertures 11 of the sheaves 10 and along the channel 8, the ends of the cable being secured to opposite ends of a carriage 30. The carriage 30 consists of a T-shaped frame having a web 31 and a platform 32 in which rollers 33 and 34 are fitted, the rollers 33 being adapted to ride upon the side walls of the channel 8 and the rollers 34 to ride upon the rails 9 thereof. Secured to each carriage 30 is a mast 35 having at its upper end a socket 36 which is adapted to swing transversely only, and the socket is adapted to receive a light rod 37 having a float 38 adjacent its upper extremity which has a buoyancy slightly in excess of that required to float its rod. The numeral 39 indicates a ship fitted with a depending sleeve 40 adjacent its bow, which sleeve is adapted to fit loosely over the upper end of the rod 37 that it may be easily detached therefrom in the event of incorrect manipulation of the device.

In the modification shown in Figure 7 the mast 35 is formed of spring wire, having formed integrally with its base a coil spring 41 so that the major portion of the mast may

Journalled upon brackets 13 carried on

give on being brought into forcible contact with any obstruction and is provided with a rearwardly and horizontally turned eye 42 which serves to receive the lower end of 5 the rod 37.

Having thus described the several parts of my invention I will now briefly explain its mode of operation.

Each player selects a ship and stations 10 himself adjacent the corresponding controls. Each ship is presumed to be adjacent the controls prior to starting. As a player pulls the upper end of his lever 22 away from the tank the corresponding arm 19 is moved 15 about the shaft 18 and the cable 27 is drawn to impart endwise movement to its carriage 30, and through its mast 35 and the rod 37 to cause the ship 39 to travel outwards to the opposite end of the tank. As certain 20 islands 6 are in the path of the ship it will obviously be necessary to alter its course to avoid them, so that by turning the steering wheel 15 to right or left as occasion demands, the track 7 and its carriage 30 are rocked, 25 thus inclining the mast 35 and moving the rod 37 transversely of the tank and drawing the ship in a corresponding direction away from the longitudinal axis of the track 7. If the steering wheel is turned too quickly for 30 the ship to respond to the turning movement, the rod 37 will become disengaged from the socket 36 or from the sleeve 40 of the ship, hence all control of its movement will be lost. If, however, the steering movement is performed with due caution, the ship 35 will move slowly and upon a substantially even keel to avoid all obstacles as it is drawn from one end of the tank to the other.

What I claim as my invention is:

40 1. An amusement device comprising a tank of water and a vessel, and manually operated means associated with the tank for propelling the vessel upon the surface of the water, said means being controllable to cause 45 the vessel to follow either a straight or an irregular path at the will of the operator.

2. An amusement device comprising a tank of water and a vessel, a track below the surface of the water, a carriage movable along 50 the track, means connecting the vessel to the carriage, and manually operable means for moving the carriage along the track, said means including provision for causing the

vessel to follow either a straight or an irregular path at the will of the operator. 55

3. An amusement device comprising a tank of water and a vessel, a track below the surface of the water defining a normal path of travel for the vessel, a carriage upon the track, means of connection between the carriage and the vessel, manually operable means for moving the carriage along the track for propelling the vessel, and means for diverting the vessel from its normal path of travel. 60 65

4. An amusement device comprising a tank of water and a vessel, a rockingly mounted track below the water level, a carriage adapted to be manually moved along the track, connecting means between the carriage and the vessel, and means for rocking the track, and means as the track is rocked beyond a predetermined speed for disconnecting the vessel from the carriage. 70

5. An amusement device comprising a 75 tank of water and a vessel, a carriage adapted to be moved along a given path below the water level by manually operable means, means for detachably connecting the vessel to the carriage, an obstruction overlying the 80 said path, and means as said obstruction is encountered by the vessel for disconnecting said vessel from the carriage.

6. An amusement device comprising a tank of water and a vessel, a hand lever upon the 85 tank, means connecting the lever with the vessel to propel it along the surface of the water, a steering wheel upon the tank, means connecting the wheel to the vessel to alter its course. 90

7. An amusement device comprising a tank containing water, and a vessel adapted to travel across the tank upon the surface of the water, a track positioned in the tank below the water level, a carriage movable along the track and connected to the vessel, means for moving the carriage along the track to cause the vessel to travel across the tank, and means for adjusting the position of the track to cause the vessel to follow either a straight or an irregular course in travelling across the tank. 95 100

Dated at Vancouver, B. C. this 13th day of July, 1928.
